UNITED STATES PATENT OFFICE.

F. JARVIS PATTEN, OF FORT SIDNEY, NEBRASKA.

ELECTRICAL-ANNUNCIATOR CALL SYSTEM.

SPECIFICATION forming part of Letters Patent No. 369,810, dated September 13, 1887.

Application filed September 25, 1886. Serial No. 214,574. (No model.)

To all whom it may concern:

Be it known that I, F. JARVIS PATTEN, a citizen of the United States, residing at Fort Sidney, in the county of Cheyenne, State of Nebraska, have invented a new and useful Form of Electric-Annunciator Call Systems, of which the following is a specification.

Figure 1 is a diagram of the combination-circuit system, showing how the required number of calls are obtained by making and breaking at different points the different possible combinations of a given number of circuits, four being taken as an illustration, giving by their use fifteen different calls. Fig. 2 shows the connections and operation of one of the combination-circuit keys used in the system. Fig. 3 is an end view of the annunciator, showing a single magnet with its drop, as well as the necessary connections inside the annunciator-box. Fig. 4 shows in diagram the face or dial of an annunciator having three (3) combination-circuit systems of four drops each and designed for thirty calls, or forty-five, at pleasure. Fig. 5 shows plan and general arrangement of a "combination push-button" for use as a "wants-call," in which one button indicates the number of the room or distant point making the call and the other push-buttons signify different wants or articles required at that room or point. Fig. 6 shows a different arrangement of the same device. Fig. 7 shows the application of such a wants-call system to an annunciator of the ordinary form for eighteen rooms, the lower row of four additional drops giving, by use of the system to be described, fifteen different calls for articles required at the rooms.

The invention consists in using a new principle in the construction of call systems, by which a given number of signals may be obtained from a similar number of distant points with a comparatively smaller number of magnets, indicators or drops, and wire circuits than are commonly used in the ordinary forms of electric annunciators. The principle applied consists in the combination of a given number of elements, the elements combined being the indicators or drops in the annunciator, as well as their corresponding wire circuits, and the key by which a number of circuits are opened and closed is designated as a

"combination-circuit key." The different signals are shown by combinations of one, two, or more of the annunciator-drops falling simultaneously and actuated by a single key or push, the number formed by the figures on the drops giving the required signal. The system will be illustrated by explanation in detail of a particular case.

Referring to Fig. 1, the four light parallel lines represent four parallel contiguous circuits, (numbered, respectively, 1, 2, 3, and 4,) each circuit controlling its own separate magnet and indicator or drop. All four circuit-wires go together from the annunciator-box successively through all the points from which indications are required and all together return to the annunciator, thus completing a closed "combination-circuit system." The following analysis of the system shows how the principle involved finds its application:

Viewed simply as elements, the figures 1, 2, 3, and 4 are susceptible when taken in combinations—first each alone, then two and two, then three and three, and, lastly, a single combination of four figures—of just fifteen different combinations, no two of which shall contain the same figures. The four figures make fifteen different numbers, as follows:

1	2	3	4	80
12	23	34		
13	24			
14				
123	124	134	234	= 4
			1234	= 1
				85
			Total	15

These are all the possible combinations that can be made with the four figures. It is evident that fifteen different points or rooms may be designated by these fifteen numbers; but in the same way four distinct wire circuits may be combined as distinct elements, each controlling a separate drop or indicator, and so give fifteen different signals with four drops and four circuits only. This is accomplished in the following manner: The points or rooms are numbered, as above described, 1, 2, 3, 4, 12, 13, 14, &c., the four circuit-wires similarly numbered w' w^2 w^3 w^4 , Fig. 1, leaving the lead u' go through all the fifteen different points, whose push-buttons are indicated by

the small squares on the circuits in Fig. 1. Starting from the left, the first point or room is designated 1234. Now the four circuits are normally all closed and the four magnets 5 m' m^2 m^3 m^4 all retain their drops by holding up their armatures; but the push-button at the point designated 1234 is so arranged that when pressed it opens simultaneously all four circuits, and all the four drops instantly fall, 10 displaying the figures 1 2 3 4 as a single number. At the next point the push-button is arranged to break only three of the circuits, leaving, say, the last, or circuit w^4 , unbroken, and the reading this push-button transmits is, 15 therefore, 123, all drops falling except the drop numbered 4. At the next point the circuit w^3 is omitted from the key, and at the next the circuit w^2 , and then w' , thus giving all possible combinations of three circuits. Then 20 the circuits are left out in pairs, of which, as we have seen, there are six possible combinations, as shown by the analysis above. They are then left out in sets of three at a time, which leaves the single figures 1, 2, 3, and 4 only, 25 thus completing the fifteen different combinations of the circuits. The particular method of arranging the key or circuit-breaker to produce these results is shown in Fig. 2, in which three of the wire circuits—viz., w' w^2 30 w^3 —enter the button and are attached to separate conducting strips a a a , fixed to a piece of wood hinged at h h . The connectors rest upon and complete the circuit through other strips, b b b , from which the circuits are continued. 35 The circuit-wire w^4 goes round this push-button and is unaffected by it, so that when this button is pressed and the contacts between the strips a a a and b b b are broken the drops 1, 2, and 3 fall simultaneously. In 40 case no two calls were ever sent at the same time nothing further would be required to complete the system, except some mechanism for resetting the drops after a signal had been received. Such a system has a variety of applications. 45 For a house-call, however, or for a wants-call, to be described later, the system requires some device to prevent the possibility of confusion resulting from two or more signals being sent at the same instant. 50 For this purpose a simple arrangement of shunt-circuits is used, which is shown in the diagram Fig. 1.

P' P is a rod upon which the different drops are hinged, as shown, and about which they turn when released.

R S is a rock-shaft placed at a suitable distance below P' P , so that any drop on falling will be caught by and rest upon R S after it has fallen just far enough to display the figure behind it. The rod P' P is a conductor, as is also the rock-shaft R S . They are, however, separated by a space, as shown. The four circuit-wires completing the circuit system return each to its own magnet-coil, whose 65 terminals v' v^2 v^3 v^4 , leaving the magnets, are all connected to the small rod x' x , a conductor connected to the opposite pole of the battery

B by the lead s c . From the other lead at the point u a shunt-circuit wire, l l' , goes through the gong G and is attached to the rod P' P . 70 Another wire, Z Z^4 , has one extremity attached to the rod R S , and connects with all the four circuit-wires w' w^2 w^3 w^4 at points z' z^2 z^3 z^4 , just above where these main-circuit wires enter their respective magnets. This shunt-circuit 75 system prevents any possible confusion of simultaneous indications. It will be observed that so long as the rods P' P and R S are separated and not in electrical connection no current can flow in the shunt-circuit, as it is discontinuous by the space separating P' P and R S ; but the drops a' a^2 a^3 a^4 are metallic and conductors. It results, therefore, that the instant any single drop is released and falls down onto the rod R S it connects this rod 80 electrically with the rod P' P , and the shunt-circuit is at once established, the current being then continuous through l l' to and through the gong G to P' P , thence through the fallen drop to R S , and thence through the wire Z Z^4 to all the magnet-coils, and through their terminals back to the battery through x' x and s c . Therefore, as long as any single drop is down, displaying its indicator, the gong 85 G will continue ringing, and will not cease to ring and signal the call until the fallen drop is restored to its place. This is effected by pulling the cord K , which rotates the rock-shaft R S and resets the drop against its magnet, where it is held. The continuous ringing of the gong insures attention to the call and prevents delay in resetting the drop. It will be further observed that as long as any single drop is down (completing the short circuit) all the magnets are thereby thrown into 90 a short circuit in multiple arc, and no other drop can be made to fall by pressing a distant push so long as one is down, thus preventing a confusion of indications.

Fig. 3 shows an end view of the annunciator, 95 in which one magnet is seen with the different connections as well as the relative positions of the rods described. The magnet m^3 , Fig. 3, is fixed at its upper extremity. Its armature a^3 is fixed to the bent lever-arm of the drop 100 D^3 . On being released the drop falls to the dotted position shown. It is evident that any number of circuits may be combined in the manner described.

Owing to the frequent necessity of transmitting a number of simultaneous calls, it will be found preferable to use several different sets of four or five wire circuits for a large number of indications, each set controlling a separate and independent row of drops. 115 This method of applying the system is shown in Fig. 4, which is a diagram of the dial or face of an annunciator arranged for either thirty or forty-five calls, divided into three sets of ten or fifteen each, each set being indicated, as before, by a row of four drops. 125 There may evidently be as many absolutely simultaneous calls as there are rows of independent drops and sets of circuits.

In Fig. 7 is shown a diagram of an electric-annunciator dial of the usual pattern for eighteen rooms, but having an additional row of four drops arranged on the four-wire combination-circuit system described, the combination system being used in this case as a wants-call, by which any number of wants up to fifteen may be signaled from any single room by means of a combination push-button placed in each room and operating, say, ten of the different combination-circuit keys shown in Fig. 1, different significations or numbers indicating different wants or articles required at the room. The different keys for this purpose may be actuated by different push-buttons, but all forming together a multiple push-button like that shown in Fig. 5, in which the central button transmits the room-call in the usual way and the ten push-buttons surrounding it signify each a different article wanted. The meaning of each number may be printed on a card near the button, or the name of the article itself may be stamped on the push-button. In Fig. 6 is shown a different arrangement of the same device.

Fig. 4 is a diagram of the front of an annunciator designed for either thirty or forty-five rooms. It has three rows of drops, as shown, which operate three separate and independent sets of combination-circuits. For convenience, the second and the third rows from the top are designated "a" and "b," respectively, and the rooms may be similarly divided into three sets, so that those in the first set and actuating the first row of drops would be rooms 1, 2, 3, 4, 12, 13, &c. These would constitute the first set, or, say, the rooms on the first floor. Those in the second set, or on the second floor, would be designated as 1^a, 2^a, 3^a, 12^a, 13^a, &c. Those in the third set, or on the third floor, would be designated as 1^b, 2^b, 3^b, 4^b, 13^b, 23^b, &c. In this manner the thirty or forty-five rooms may be designated and transmit their calls with twelve drops only.

Having thus described my invention, what I claim, and desire to secure by Letters Patent, is the following:

1. A combination electric-annunciator call system having a number of contiguous parallel electric circuits operated by means of a number of combination-circuit keys, corresponding to the different possible combinations, no two alike, of the given number of circuits, each key connected through said circuits to a corresponding combination of annunciator-drops. 55

2. In an electric annunciator, the combination of two or more independent combination-circuit systems, each separate wire system connected to a separate set or row of drops in the annunciator. 60

3. In an electric annunciator, the combination of a number of different sets or rows of drops with lettered drops or indicators, one for each such set or row. 65

4. A multiple push-button or circuit-controller consisting of a number of distinct push-buttons, each operating a separate combination-circuit key, all arranged in a number of contiguous parallel circuits, and connected thereby to a like number of annunciator-drops. 70

5. In a combination electric annunciator, the connections described of an incomplete or open short circuit, which includes all the magnet-coils of the combination-circuit system in multiple arc between its terminals, said connections being so placed with respect to each other that a fallen drop, by connecting the rod about which it turns with that upon which it falls, throws all the magnets of the combination system into said short circuit. 75 80
